DRILL END SHARPENING MEANS

Edward C. Kapnick, Adrian, Mich.

Application January 28, 1949, Serial No. 73,240

10 Claims. (Cl. 51—219)

1
This invention relates to tool grinding apparatus, and particularly to such apparatus adapted for grinding and sharpening drill ends.

The primary object of the invention is the provision of a simple and efficient holding means for drills, which means is operable during a drill grinding or sharpening operation to impart a compound movement to the drill end during grinding, whereby the drill end is both shifted across the grinding face throughout a predetermined path and is also rocked to accurately move the drill end during such movement, thus avoiding the forming of pits and narrow grooves in the working face and obviating the necessity of frequent dressing of the wheel surface and also grinding an arcuate end part of the drill end. This action also results in a keener and more uniform cutting edge on the drill.

Other objects and advantages of the invention will be apparent from the following detailed description, and from the accompanying drawings illustrating one embodiment of the invention, in which—

Fig. 1 is a side elevation of an apparatus embodying the invention, with a drill held thereby in sharpening engagement with a grinding wheel, with parts broken away; Fig. 2 is an end elevation thereof, with parts broken away; Fig. 3 is a fragmentary sectional detail on the line 3—3 in Fig. 1; Fig. 4 is an inner fragmentary side view of the drill holder turning means for imparting arcuate movements to the drill end; Figs. 5 and 6 are sections on the line 5—5 in Fig. 1, with the drill clamping means closed and open, respectively, and with a portion of the former broken away; Figs. 7, 8 and 9 are diagrammatical views showing the position of a drill relative to the grinding wheel in different stages of its movements during a grinding operation; Fig. 10 is a section on the line 10—10 in Fig. 1, and Fig. 11 is a similar view with the clamping member thrown to released position.

Referring to the drawings, 1 designates the frame of a grinding machine with the grinding wheel 2 thereof, in the present instance, mounted for rotation in a vertical plane and having its outer side exposed for engagement therewith of the work to be ground. The frame has a ledge or part 3 projecting horizontally from the side thereof at which the grinding wheel is disposed and a distance below said wheel to support the work holding and adjusting mechanism in which the features of the present invention reside.

This mechanism comprises, in the present instance, a base block 5 of inverted U-form in

2
cross-section with its legs resting on the top of the frame part 3, and engaged by gibbs 6 on said part to guide the block for sliding movements toward and away from the frame. The top 7 of this block is of concaved arcuate form with the arc extending outward and upward from its inner end to define a rise from a horizontal of somewhat over 140°.

Longitudinal adjustment of the block 5 is effected by turning a cam 8 between the legs of a U-shaped cradle 9 that is mounted on the frame part 3 between the legs of the block 5, in gibbs 10 for free limited yielding movements between stops 11, 11. The cradle 9 is yieldingly urged in one direction by a spring 12 attached to the frame 1 and in the opposite direction by a spring 12a attached to a screw 13. The spring 12 is somewhat the stronger of the two so as to normally hold the cradle 9 in engagement with the inner stop 11. The stops 11 are so positioned with respect to the cradle as to permit only a very limited movement of the cradle therebetween. The shaft 14 to which the cam 8 is fixed is journaled in suitable bearings in the respective legs of the block 5 and has a control handle 15 at one end. The throw of the cam imparts a maximum movement to the block 5 substantially as indicated at 16 in Fig. 1. The inward movement of the block is limited by an adjusting screw 17 on the frame 1.

A drill holding standard 20 is mounted on the arcuate top 7 of the base block 5 for adjustment lengthwise thereof whereby the tilt of the standard relative to the plane of the working face of the grinding wheel 2 may be varied. A degree scale on the side of the block indicates the angle of inclination.

The standard 20 comprises a base member 21 mounted on the arcuate top of the base block 5 for adjustment lengthwise thereof, an intermediate member 22 mounted for transverse adjustment on the member 21, and a top drill-holding member 23 mounted for rotary adjustment on the member 22.

The base member 21 rests on the arcuate top of the block 5 and in the present instance has opposing side plates 24 held to the member by suitable screws 24a and extending below the edges of the member to have guiding engagement with the block 5, and also extending above the top of the member. The member 22 is narrower than the space between the side plates 24 and has sliding dovetailed engagement with the member 21 for limited reciprocating movements

A tension rod 25 extends through a slot in the arcuate top of the block 5 and has its upper end in engagement with the offset portion of an eccentric shaft 27 mounted crosswise in the members 21 and 24. One end of the shaft is provided with a knob 28 to facilitate turning. A coiled expansion spring 26 on the lower end of the rod 25 coacts with a nut or shoulder on the rod and with the under side of the arcuate top of the block 5 to hold the rod under tension when the shaft 27 is turned to the position shown in Fig. 3, whereby to exert a block-clamping tension on the rod. It is apparent that when the shaft is turned to place the eccentric portion in lowered position the block 21 can be freely shifted on the block 5 to place the former in desired position thereon to suit the tool-dressing angle.

The top member 23 rests on the top of the member 22 and has a stub shaft 30 fixedly projecting therefrom into a bearing in the member 22, with the shaft axis lengthwise of the standard at right angles to the plane of relative adjustment of the members 21 and 22, as indicated by the dotted line *a* in Fig. 1. The shaft 30 intersects an opening 31 in the inner side of the member 22 and within this opening a cable 32 is wound one or more times around the shaft and fixed thereto and its ends are extended laterally in opposite directions from the shaft through registering openings in the member 22 and anchored to the upper ends of the respective side plates 24, as best shown in Fig. 4.

It is apparent that movements of the member 22 in opposite directions on the member 21 will cause the stationary cable 32 to turn the shaft 30 and drill-holding member 23 in one direction or the other relative to the member 22.

Fixed to the upper end of the member 23, in inclined relation to its rocking axis *a*, is a drill-holding cradle 34. This cradle comprises a bar 35 that is fixed at an incline on the upper end surface of the member 23 by a screw 36, and is provided at its upper or front end with an upstanding drill rest 37 and rearwardly therefrom with a longitudinally adjustable drill rest 38. Each of these rests is provided in its top with aligned V-grooves 39 for receiving a drill 40. The drill rest 38 is provided at its rear end with an adjustable screw stop 41 for the drill and at its forward end with a hinged clamp frame 42. This frame has a drill engaging jaw 43 that is inclined to have camming engagement with a drill when clamped down thereon. The jaw 43 is slidable lengthwise in the frame 42 and is urged toward the work by a spring 44, the tension of which is adjustable by a screw 45. The jaw 43 is also urged sidewise in the frame by a flat corrugated spring in the side of the frame. The frame 42 is held in clamped position by a pin 46 inserted into registering lapping portions of the parts 38 and 42. The tool rest 38 is held in adjusted position on the bar 35 by a conventional clamping screw means the screw shaft of which is operated by a handle 47.

A front drill clamp 50 is attached to the forward end portion of the bar 35 adjacent to the front rest to cooperate therewith to clamp the front end portion of the drill. This clamp comprises a stem 51 pivoted at its lower end for swinging movements lengthwise of the bar 35 to a block that is slidably mounted on the bar. The sliding of the block on the bar permits adjustment of the holder to drills with fast or slow spirals. Mounted on the stem 51 for limited reciprocating movements is a sleeve 52 having an

arm 53 projecting radially therefrom. The movements of the sleeve on the stem are guided by a pin 54 in the stem projecting into a longitudinally extending slot 55 in the sleeve. The lower end of the slot has a lateral extension to permit the sleeve and arm to be given a quarter turn on the stem when raised a distance against the tension of the spring 56 on the upper end of the stem. The arm 53 is adapted to swing over a clamped drill 40 and is to be held in downwardly pressed engagement therewith. This arm has a spring-pressed finger 57 for engagement in a groove of the drill against a land thereof. This finger has pin-and-slot connection with the arm and is yieldingly projected by a spring 58.

In an operation of the device, a drill 40, preparatory to being ground, is placed in the rests 37, 38, with its forward end projected a desired distance from the former for grinding by a proper adjustment of the stop screw 41 which determines the desired extent of projection of the end of the drill beyond the axial line *a*. The clamping frame 42 is then swung over in drill-holding position and is held in such position by the pin 46. The clamping jaw 43 yields to adjust itself to the diameter of the drill. The clamping arm 53 is also moved into position to engage over the front end portion of the drill in opposition to the rest 37 with the finger 57 projecting into a drill groove. The standard base member 21 is now adjusted on the arcuate top 7 of the base block 5 to place the lower side of the conical cutting end of the drill 40 parallel to the outer side face of the grinding wheel 2, such facing being indicated at *b*. The pressure of the drill end against the wheel is determined by the tension of the spring 12 acting on the block 9 and through it and the cam 8 and its shaft 14 on the base block 5. The stop screw 17 limits the extent of inward movement of the block 5 and parts carried thereby relative to the machine frame 1. After a dressing of the face *b* of the grinding wheel the screw 17 may be adjusted to compensate for the dressing or the wheel 2 may be moved over for the purpose. As the grinding progresses the drill end is moved backward and forward across the face of the wheel 2 substantially radially of the wheel axis by a backward and forward movement of the member 22 on the member 21 combined with the rocking movement about the axis *a*, which latter movement is actuated by movement of the shaft along the cable 32. The movement of the drill end relative to the wheel face is diagrammatically illustrated in Figs. 7, 8 and 9, wherein the line *c* indicates the length of transverse movement of the drill end on the wheel, or the width of the circular grinding path of the wheel face, and *d* indicates the rocking axis at the point of intersection with the drill axis. It is apparent that the drill end has a triple compound movement: (1) linear reciprocatory movements of the point *d* on the line *c* corresponding to the linear movement of the member 22 on the member 21; (2) arcuate movement of the drill point about the axial point *d*; and (3) the arcuate rolling movement of the conical end surface of the drill, both movements (2) and (3) being occasioned by the rocking of the members 23, 34, about the shaft axis *a*. This not only effects a grinding of a predetermined arc of the conical end surface of a drill, but also distributes the grinding over a relatively broad area of the wheel surface, thus preventing the formation of pits and grooves in the wheel surface and obviating the necessity

of frequent dressing for trueness. After one arc on the conical end surface of the drill has been ground, the drill is rotatably shifted in the holder, without removal therefrom, to bring successive arcs into grinding position and the grinding action is repeated for each such adjustment of the drill.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a drill grinding machine having a grinding wheel, means for holding a drill with its cutting end in engagement with the wheel and mounted for rocking movements about an axis intersecting the drill axis at a point adjacent and spaced rearwardly of the cutting end of the drill, means carrying said first means and operable to shift it transverse to said rocking axis and to the drill axis, means carrying said second-mentioned means and guiding its transverse shifting movements, and means including a shaft on said first means and a connection between said shaft and third means operable to impart rocking movements to said first means when said second means is shifted.

2. The combination with a rotary grinding wheel, of means for holding a drill in end engagement with a grinding surface of the wheel, a mount carrying said means for rocking movements about an axis which intersects at an acute angle the axis of a drill held by said means with the point of intersection adjacent to the end of the drill to be ground, means supporting said mount for limited linear reciprocatory movements transverse to said rocking axis and parallel to the wheel surface engaged by the drill, and means including a shaft and cable connecting said mount and drill holding means and operated by reciprocatory movements of said mount to permit rocking movements to said first means, the degree of rocking depending on the range of movement of the mount.

3. An apparatus for holding a drill with its cutting end in sharpening engagement with a grinding wheel, comprising a standard having a base, an intermediate member and a drill holder, said member being mounted on the base for predetermined shifting movements along a straight line relative thereto and said drill holder being carried by said member for rocking movements about an axis which is perpendicular to said line of movement of the member and also intersects the axis of a drill carried by the holder, means including a shaft on said holder mounted in said member and a connection between the shaft and said base operable to rock said holder about its axis when the member is shifted on said base, whereby a compound movement is imparted to the end of the drill being ground.

4. An apparatus for holding a drill with its cutting end in sharpening engagement with a grinding wheel, comprising a base, a member mounted for reciprocatory movements on said base along a straight line, a drill holder mounted for rocking movements on said member with its rocking axis perpendicular to said line and intersecting the axis of a drill carried thereby with the drill axis inclined to the rocking axis, and means connected to said holder and said base and actuated by reciprocatory movements of said

member to impart predetermined rocking movements to the holder, whereby a drill during grinding has compound movements imparted thereto.

5. An apparatus for holding a drill with its cutting end in sharpening engagement with a grinding wheel, comprising a base, a member mounted for reciprocatory movements on said base along a straight line parallel to the wheel grinding face engaged by the drill, a drill holder carried by said member and rockable about an axis perpendicular to said line and adapted to hold a drill with its axis intersecting at an acute angle said rocking axis adjacent to the end of the drill to be ground, and means including a shaft on said holder and a connection between said shaft and said base for rocking said holder when said member is reciprocally moved on the base, whereby compound movements are imparted to the end of a drill being ground.

6. An apparatus as called for by claim 5, wherein the drill axis is inclined to both said rocking axis and to the grinding face.

7. An apparatus for holding a drill with its cutting end in sharpening engagement with a grinding wheel, comprising means for supporting a drill in grinding relation to the wheel and including a base, means mounting said base for predetermined arcuate shifting movements in a plane transverse to the wheel grinding face, a member slidably mounted on the base for movement along a straight line parallel to the axis of said arcuate movement and relative to the grinding face of the wheel, a drill holder mounted on said member for movements therewith and for rocking movements relative thereto about an axis perpendicular to said line, said drill holder having means for holding a drill with its cutting end in grinding position and with its axis intersecting said rocking axis adjacent to said cutting end, and means connecting said base and drill holder and automatically operable to rock said holder when said member and base are relatively shifted.

8. An apparatus for holding a drill with its cutting end in sharpening engagement with a grinding wheel, comprising a drill holder for carrying a drill with its axis angular to a face of the grinding wheel and its cutting end in position to be ground, a standard carrying said holder, a supporting base mounting said standard for sliding movements along a straight line parallel to the grinding face of the wheel, a sub-base for said supporting base having an arcuate face on which the supporting base is mounted for tilting adjustment in a plane transverse to the grinding wheel face, means holding said supporting base in adjusted position on said sub-base, said holder having a shaft fixed to said holder and rockable about an axis intersecting a drill axis adjacent to its carrying end, and means connecting said shaft and supporting base and operable by relative sliding movements of said standard and supporting base to rock said shaft and holder relative to the standard.

9. An apparatus for holding a drill with its cutting end in sharpening engagement with a grinding wheel, comprising a grinding wheel, a standard for holding a drill with its cutting end in grinding wheel engaging position and with its axis angular to the wheel face, said standard having a base, an intermediate member transversely shiftable on the base along a straight line, and a drill holder rockable on the intermediate member about an axis intersecting the

drill axis adjacent to its cutting end and also perpendicular to the shifting line of the intermediate member, a rocking shaft fixedly projecting from the drill holder and journaled in the intermediate member, and a cable wound around and fixed to said shaft with its opposite ends attached to portions of said base at opposite sides of the intermediate member whereby shifting movements of the latter along the cable impart relative rocking movements to the shaft and drill holder.

10. An apparatus as called for in claim 9, together with an adjustable support for the base whereby the standard may be adjusted relative to a grinding wheel.
